UNITED STATES PATENT OFFICE

THEODOR R. WILLWERSCHEID, OF CLEVELAND, OHIO

REFLECTING BUTTON FOR SIGNS

Application filed August 26, 1929. Serial No. 388,451.

My invention relates to improvements in reflecting buttons for signs, of the type wherein glass buttons are positioned in openings in a sign plate to spell out the letters or characters of a sign.

In the usual construction, the glass button employed for this purpose, is held within a housing, which housing, back of the button, constitutes a reflecting surface to reflect rays of light passing into and through the button.

An object of my invention is to eliminate the use of such housing and embody the reflecting surface within the button itself.

15 This and other features of my invention will be more specifically set forth in the following description and the accompanying drawing, wherein:

Figure 1 is a partial view of the face plate 23 of a sign with my improved button positioned within an opening in said plate; and

Figure 2 is a section on line 2—2 of Figure 1.

In carrying out my invention in the form 25 illustrated, I embed within the bottom of the button 2 a reflecting plate 3, the reflecting plate 3 being properly curved in relation to the curved outer face 4 of the button to reflect the rays of entering light at the desired 30 and proper angles. This reflecting plate 3 may be of any suitable reflecting material, and preferably is enough narrower than the width of the button so as to reflect all rays 35 out through the projecting face of the button and prevent any of those reflected rays striking the side walls of the button holder.

In the drawing, I show a preferred form 40 of holder for this button, consisting of a split metal ring 5, having an exterior groove 6 in its outer edge to receive the edge of the sign plate A. The bottom 7 of the ring is bent inwardly under the button to hold the buttons clamped in position.

45 In the form shown, the button is formed with a shoulder 8 which will contact with the portion of the ring forming the groove 6, so that the button is clamped between said flanged portion 6 and the bottom of the ring.

50 By having the reflecting surface a part of the button itself, instead of part of an en-

closing housing, I am able to protect the reflecting surface against damage through being exposed, and am able to position it in any desired relationship to the face of the button, and to save the expense and inconvenience of an enclosing reflector housing.

By means of the construction shown, I not only save the expense of a special housing for the glass button, but am enabled to position the reflecting plate 3 at any desired distance from, and in any desired relation to the exposed surface of the button, and, am thus enabled to regulate the angles of refraction, as desired.

I do not, however, restrict myself to this particular form of holding the button in position, nor to the particular shape or form of button shown, the scope of my invention being set forth in the accompanying claims.

I claim:

1. A light reflecting unit, comprising a one-piece glass button, a reflecting unit imbedded within said button in opposition to the exposed face of the button and spaced from the rear end of the button.

2. A light reflecting unit, comprising a solid, one-piece glass button having a curved face, an oppositely curved reflecting unit imbedded in said button in opposition to the curved face of the button, and spaced from the rear end of the button.

In testimony whereof I affix my signature.

THEODOR R. WILLWERSCHEID.
